United States Patent Office.

J. DEAN BONNEY, OF PEMBROKE, MASSACHUSETTS.

Letters Patent No. 94,179, dated August 31, 1869.

IMPROVED SPRING-SEAT FOR CHAIRS, CARS, CARRIAGES, &c.

The Schedule referred to in these Letters Patent and making part of the same.

To all to whom these presents shall come:

Be it known that I, J. DEAN BONNEY, of Pembroke, in the county of Plymouth, and Commonwealth of Massachusetts, have made a new and useful invention of an Improved Spring-Seat for Chairs or for Railway-Carriages or other Conveyances; and do hereby declare the following to be a full, clear, and exact description thereof, due reference being had to the accompanying drawings, making part of this specification, and in which—

Figure 1 is an inverted perspective representation of the interior of a seat in which my invention is embodied;

Figure 2 being a vertical section of the same.

The object of the invention comprising the subject-matter of this patent is to provide a seat or rest for use in various land-conveyances, or for bed-bottoms, &c., which shall possess the properties of strength, durability, and cheapness, combined with sufficient flexibility to vitiate the jarring of the carriage; the seat, under my construction of parts, also presenting an even and smooth appearance of its side covering, under all conditions of service.

The invention consists in the employment of two open or skeleton frames, of equal size, or thereabout, placed one over the other, and connected together primarily by a dually-arranged series of springs which perform the offices both of hinges to the two frames and as a yielding support to the uppermost one; and secondarily, by a surrounding band of any suitable textile fabric, which serves as an edge to the seat formed by the two frames, and partially as a stop to limit the distance of separation of such frames, the top of the seat being composed of a stuffed cushion, applied to the upper frame, the whole being as hereinafter referred to and explained.

By referring to the drawings above mentioned as accompanying this specification, and which illustrate my invention, it will be seen that A A' denote two open rectangular flat frames, of about equal size, composed of wood or any suitable material.

These frames are placed one over the other, are united in part and principally by a series of springs, a a a, &c., placed between them, the two frames being placed at such a distance apart as to present the proper height for a portable seat for various conveyances, vehicles, or articles of furniture.

The springs a a are each composed of a concentric coil, b, and two lateral prongs, c c, the latter being prolongations of the extremities of the coil, and running in about the same direction, and horizontally parallel to each other, as shown in fig. 2 of the drawings.

In applying the springs a a, &c., to their proper place, I affix the extremity of one prong in a suitable

manner to one of the bars of one frame, and its fellow prong to the next adjacent bar of the opposite frame, and I employ as many of these springs running longitudinally of the two bars, as practice may determine to be necessary or desirable, the two opposite bars of the frames A A' being provided, in like manner, with a corresponding number of springs.

I would call attention to the fact, that in fixing the springs a a in position, I dispose the upper prong of each spring upon alternate sides of its coil, in order to prevent lateral swaying of the two frames, which would take place out for such disposition of the springs, or other extraneous means to accomplish such end.

A rod, B, is extended through the bores of each range of springs, to support them in alignment with each other, and, in some instances, to prevent too great contraction of the coil.

The cushion of the seat is shown at C in the drawings, as composed of any suitable fabric or material, and proper stuffing, after the common method of producing such articles, such cushion being affixed to the upper frame A in manner as will readily manifest itself to builders of railway-carriages or vehicles of any description, or of bed-bottoms or other articles of furniture.

The outer edges of the frames A A are united by a circumscribing-band, D, of fabric similar to that of the cushion C, the two frames, in addition to such band, being furnished with a number of stays, d d, &c., of webbing or other strong material secured to each, for the purpose of relieving the band D of the strain which would otherwise be exerted upon it by the extension of the springs a a, it being understood, however, that the length of these latter-mentioned stays between the frames A A' is equal to the corresponding width of the band D, in order that the latter shall be preserved in an extended and smooth state upon divergence of such frames by the action of the springs, which takes place when the occupant's weight is removed therefrom.

To the outer extremity of each rod B, and the two frames A A', I affix a strap, as shown at E, in the accompanying drawings, as an additional, though not necessary support to such parts.

In practically carrying out of my invention, it will be found desirable to vary the power, as well as the number of the springs, according to the various uses to which the seat is to be put.

One advantage resulting from the above-described arrangement of parts is that as the springs are not applied directly to or below the cushion, the unequal pressure, as well as rapid wear of seats thus provided, is avoided, and in this respect, as well as others, will make a valuable bed-bottom.

Another advantage of my invention is that the

edge of the seat does not remain in a ragged and rumpled state after the weight upon it is removed, as the two frames are forced apart, and the band tightened by the action of their springs, instantaneously with such removal of such weight from the upper one.

Another advantage of my improved seat is that dust and dirt may be easily expelled from its cushion.

In addition to these advantages, my invention enables a spring-seat to be manufactured at small comparative cost.

Claim.

Having thus described the nature and advantages of my invention,

What I claim as novel and original in such invention, and desire to secure by Letters Patent of the United States, is—

The improved spring-seat or bed-bottom before described, consisting of the two frames A A' united by the springs *a a*, &c., and provided with the cushion C and band D, as explained, and with the stays *d d*, &c., as accessories to the band, the whole being arranged and operating essentially in manner as hereinbefore set forth

J. DEAN BONNEY.
